BY J. O. Richey
His ATTORNEY

UNITED STATES PATENT OFFICE.

RAY H. MANSON, OF ELYRIA, OHIO, ASSIGNOR TO THE GENERAL PHONOGRAPH MANUFACTURING COMPANY, OF ELYRIA, OHIO, A CORPORATION OF OHIO.

PHONOGRAPH.

1,419,938.

Specification of Letters Patent. Patented June 20, 1922.

Application filed January 13, 1916. Serial No. 71,813.

To all whom it may concern:

Be it known that I, RAY H. MANSON, a citizen of the United States, residing at Elyria, in the county of Lorain and State 5 of Ohio, have invented certain new and useful Improvements in Phonographs; and I do hereby declare the following to be a full, clear, and exact description of the invention, such as will enable others skilled 10 in the art to which it appertains to make and use the same.

My invention relates to phonographs, and more particularly to sound boxes and sound 15 conducting arms, the objects of my invention being to increase the efficiency of such devices and to provide devices which can be more conveniently and cheaply made than those at present in use.

Other objects of my invention and the 20 invention itself will probably be better understood from a description of an embodiment of the invention.

Fig. 1 is a front elevation of an embodiment of my invention.

Fig. 2 is a plan view showing the sound 25 box in section.

Referring now to the drawing and to the embodiment of my invention illustrated therein, at 10 is shown a cup whose bottom 30 11 is provided with an opening 12 to which the sound arm 13 is connected. The sides of the cup are shown at 14. In the embodiment shown, the cup consists of a shallow, cylindrical body, which is preferably formed from a single piece of metal.

This cup may be punched up. The rim of the cup is beveled, as shown at 15, preferably away from the interior of the cup, for a purpose to be described. The interior 40 of the cup is shown at 16. A flexible gasket 17 is placed in the interior of the cup, preferably upon the bottom of the same. This gasket may consist of a hollow rubber tube, as illustrated in the drawing, or of any other suitable form.

The sound diaphragm is shown at 18, which is placed in the cup on top of the gasket 17, and which extends over substantially the whole cross-sectional area of the 45 cup. This diaphragm may be made of any suitable material. A second flexible gasket is shown at 19, which may be similar in construction to the gasket 17, and which is mounted in the cup on top of the diaphragm 50 and around the edge of the cup. The front

of the cup is shown at 20. The bottom of the front is shown at 21, the outer side wall at 22 and the inner side wall at 23. A collar 24 is provided, here shown as integral with the outer wall of the cup; in 60 fact, in the embodiment illustrated, it is shown as an extension of its outer wall.

When the front is in position upon the cup, the collar 24 engages the side of the cup and holds the front in position. In 65 the form shown this is done by means of frictional engagement between the collar and the side of the cup. A flange 25 is provided upon the inner wall 23 of the cup, preferably extending substantially at right 70 angles from said wall, and engaging the outer gasket 19, holding the gaskets and diaphragm in position. It will be seen that by beveling away the rim 15 of the cup, I provide means whereby the cup may be 75 guided smoothly into position. At 26 is shown means for operating the diaphragm. This means consists of a stylus 27, a stylus support 28 and a stylus bar 29. The members 27, 28 and 29 are supported from the 80 stylus frame 30, which consists of a base member 31, provided with a wing 32 to which the members 28 and 29 are connected. The stylus frame engages a pair of knife-bearings 32' and is held in position in such 85 bearings by springs 33 mounted upon screws 34. I have illustrated this particular form of stylus and stylus support, though it will be apparent that any suitable form may be 90 employed.

The sound arm 13 is formed of a plurality of longitudinal members 40 and 41, each of which may be stamped out, and each of which is provided with a flange, the member 40 with a flange 42 and the member 41 with a flange 43. When connected together, these flanges engage each other, stiffening the sound arm, as well as maintaining a suitable connecting means therefor. One end of the sound arm is provided with an 100 elbow 50, which joins the sound box. The sound box and the members 40 and 41 are connected together preferably by a single member, such as a screw 51, which passes through both the members 40 and 41 into a 105 threaded opening 53 in the sound box. The members 40 and 41 are expanded at their free ends, as shown at 60 and 61, the expansions taking in general substantially the shape of a portion of a globe. Through 110

these expanded ends, the arm 13 is connected to a megaphone or resonator.

While I have shown this particular form and these details of my invention for the purpose of being better able to describe the same, I do not wish to be limited to such form and details, as it will be apparent that I may make many departures therefrom and changes therein, without departing from the spirit of the invention.

I claim:—

1. In a talking machine, the combination of a relatively heavy shallow circular cup having a perforation in the central part of the bottom thereof for the connection of a sound arm, a flexible gasket in the bottom of said cup adjacent the side thereof, a vibratory diaphragm in said cup on said gasket, a second flexible gasket similar in general to the first gasket on said diaphragm and within said cup, the peripheral edges of the diaphragm being positioned between the gaskets, a front for said cup consisting of a flat-bottomed annular member adapted to extend over the edge of the cup, the outside wall of the front being substantially perpendicular to the bottom of the front and extending upwardly to form a collar adapted to frictionally engage the outside of the side of said cup to hold the front in position on the cup, a flange on the inner wall of said front substantially at right angles to the walls of said front, said flange extending over the second named

gasket engaging the same and retaining said diaphragm and gaskets in position, and the top edges of the cup beveled away whereby said cup may be guided smoothly into position.

2. In a talking machine the combination of a shallow cup, a diaphragm and a pair of gaskets in said cup, a sheet metal front for the cup consisting of an annular member provided with a bottom, an inner wall and an outer wall, the bottom being of substantially the same width as the edge of the sides of the cup, a collar integral with the front on the outer wall of the front adapted to engage the cup to retain the front on said cup, and a flange integral with the front on the inner wall of the front to retain the diaphragm and gaskets in said cup.

3. In a talking machine, the combination of a cup, a pair of flexible gaskets in said cup, a vibratory diaphragm between said gaskets, and a front on said cup consisting of an annular trough adapted to frictionally engage the sides of said cup, the extremity of the inside wall of said front being bent at right angles to the other portion thereof, and adapted to engage one of said gaskets.

In witness whereof, I have signed my name hereunto this 8th day of January, 1916.

RAY H. MANSON.
